COMPOUND OUTLET VALVE FOR FAUCETS

Montague H. Duval, Great Neck, N. Y.

Application August 13, 1945, Serial No. 610,439

6 Claims. (Cl. 277—43)

1

This invention relates to outlet valves of the type which are applied to or mounted on the delivery spouts of water faucets for the purpose of controlling the outflow of water at that part of the faucet. It is particularly intended and adapted for controlling the delivery of water for washing and rinsing of dishes and other tableware.

Among the objects of the invention are to provide in such a valve means by which either a spray of water or a copious discharge may be delivered at will; to provide means whereby the valve may be held in position for delivering either a spray or copious supply of water for an indefinite time without the attention of the operator; and to enable a rinsing spray to be delivered while pressure is maintained on a controller by a person's hand or by a dish held in the hand and automatically shut off when such pressure is discontinued. Other objects are concerned with structural features and connecting means described in the following specification and illustrated in the accompanying drawings.

In the drawings—

Fig. 1 is a side elevation of a valve attachment embodying this invention applied to the outlet terminal of a water faucet spout of the swinging type;

Fig. 2 is a sectional view of the valve taken on line 2—2 of Fig. 4;

Fig. 3 is an elevation of the valve casing detached from other parts;

Fig. 4 is a horizontal section of the valve taken on line 4—4 of Fig. 2;

Fig. 5 is a sectional view of a part of the valve casing and attaching means showing an alternative means for attaching the valve to the faucet terminal;

Fig. 6 is a cross section taken on line 6—6 of Fig. 5;

Figs. 7 and 8 are views similar to Fig. 5 showing other alternative means for attaching the valve to a faucet;

Fig. 9 is a sectional view similar to Fig. 2 showing another embodiment of valve having means for accomplishing the objects hereinbefore set forth;

Fig. 10 is a plan view of the valve elements forming part of the combination shown in Fig. 9;

Figs. 11, 12 and 13 are sectional views taken on line 11—11 of Fig. 9 showing the movable parts of the valve in their different operative positions.

Like reference characters designate the same parts wherever they occur in all the figures.

The valve includes a body or casing 15 which is connected to the faucet extremity by any one

2

of a variety of means later described, and has an entrance opening at the end which is placed next to the faucet and a delivery spout 16 at the opposite end. It contains an internal annular shoulder 17 provided with a seating face on the upper side of its margin against which a valve body or element 18 is normally seated.

This valve body may be called the main valve. It has a passage through it with a valve seat at 10 the upper end on which a secondary valve 19 is adapted to bear, and normally bears, for closing the passage.

Preferably the main and auxiliary valves are combined in a unit assemblage. A suitable construction of such an assemblage is shown in Fig. 2. Here the main valve element 18 is a disk of suitable material, which may be metal, rubber composition, fiber, etc. It is made with a central opening in which is contained a tube 20 having 15 a flange 21 at its lower end underlying the valve element 18, and its upper end protrudes above the valve element and is externally threaded. A perforated dome 22 enveloping the secondary valve 19 is screwed on the threaded end of tube 20 and has a peripheral flange 23 overlying the upper side of valve disk 18. The latter is firmly clamped between the flange 21 and the dome. Valve 19, which is preferably a ball, is confined within the perforated dome or cage 22, and seats 20 against a seating surface formed in the upper end of the tube or sleeve 20. Both valves are normally held in closed position by gravity and by the pressure of water existing in the faucet spout when the valve which admits water to the faucet is open.

It may be noted here that the faucet spout 24 shown in Figs. 1 and 2 is of a type commonly installed in relation to dish washing sinks, swiveled to a fixture which is connected with both 35 hot and cold water pipes, each of which is controlled by its own valve. Such spouts are commonly formed with a marginal bead 25 at their outlet end, and the coupling shown in Figs. 1 and 2 by which the valve casing is attached to the faucet is designed for accommodation to spouts of this type.

The coupling consists of a tube or sleeve 26 having an internal shoulder 27 at one end and being internally threaded at the opposite end to engage external threads 28 on the valve casing 15. The diameters of the sleeve 26 and of the space within the shoulder 27 are large enough to permit the sleeve to be passed over the terminal bead 25 and around the bend of the spout 50 which is located a short distance above the ex-

tremity. A rigid washer 29 is located within the sleeve 26 abutting against the flange 27 and has an internal diameter which is smaller than that of the shoulder 27 but large enough to pass over the bead 25. A packing ring 30 of rubber composition or other suitable elastic, flexible and water impervious material is placed to surround the extremity of the faucet and project from the end thereof. It may be formed with an internal groove to receive the bead 25 and with internal diameter smaller than that of the bead at each side of the groove. It is stretched in being applied to the faucet. Sleeve 26 and washer 29 are slipped back over the faucet spout to leave the extremity thereof clear for application of the packing ring, and are afterwards slipped forward so that the end of the sleeve protrudes beyond the extremity of the spout. The valve casing is then screwed into the sleeve sufficiently to compress the packing ring between the end of the casing 15 and the washer 29 and hold it in tight supporting engagement with the faucet and sealing contact therewith and with the valve casing.

The secondary valve 19 can be opened independently, and both valves opened together, by a valve operating member or actuator which, in the embodiment now being described, consists of a ring 301 having two or more radial arms 31 joined to a central hub 32, and a tube 33 secured to the hub. The ring 301 surrounds the valve casing 15 and is preferably provided with a cushion ring 34, which may be a ring of rubber composition in which a flange on the actuator ring 301 is embedded, substantially as shown. Arms 31 are spaced substantially equiangularly around the center of the actuating ring and pass through inclined slots 35 in the sides of the casing 15; such slots being related to the arms in such manner that all of the arms can be placed at the lower ends of their respective slots at the same time and are then supported stably with the plane of the actuator ring perpendicular to the axis of the valve casing.

When the actuator is in the position last mentioned, the hub 32 is spaced a short distance below the flange 21 which underlies the main valve body 18. Tube 33 extends through this hub and its upper end passes through the bore of tube 20 with sufficient clearance to be capable of moving freely therethrough and to avoid binding if it is somewhat inclined when being raised. The upper end of the tube terminates so close to the under side of the secondary valve element 19 that it will unseat the valve when raised by even a slight distance. In the side walls of the tube at the upper end are notches which act to break up water flowing when the secondary valve is unseated so that the water issues from the tube as a spray. What water then flows through the annular space around tube 33 in the bore of the tube 20 strikes the hub 32 and is also broken into a spray.

When the actuator tube is rotated, the under faces of the inclined slots 35 cause it to be raised with the effect, first of unseating the secondary valve 19; and then, if the movement is continued far enough, of unseating the main valve 18. Engagement of the hub 32 with the flange 21 and continued upward movement thereafter causes the main valve to be unseated.

Shallow notches 36 and 37 are formed in the bottom edge of each inclined slot 35 at an intermediate point and at the upper end respectively. The notches 36 are suitably located to retain the actuator ring in the position where it

holds the secondary valve 19 open but does not open the main valve; while the notches 37 retain it at a high enough elevation to hold the main valve open. Thus the actuator may be placed, and left without further attention, in position for causing either a spray of water to pass through the main valve, or a copious flow of water to pass around the main valve. When the actuator rests at the low end of the slots, it may be lifted, without rotation, by upward pressure of a person's hand, or pressure exerted through a dish held in the hand enough to open the secondary valve only for emission of a spray, and the slot is wide enough to permit this action. When the pressure is relaxed, the water is automatically shut off. Thus a dish washer can take a dish from a sink or pan containing soapy water and, by pressing upward with his hand or the dish on the cushion ring 34, cause the dish to be rinsed by a spray of clean hot water; and this without either turning the faucet valve handle or wasting hot water. But when a continuous spray is required, this can be obtained by turning the actuator so that its arms occupy the notches 36. Similarly a full stream for filling a sink or dish pan can be caused to emerge by turning the actuator into engagement with the notches 37.

In order to permit assemblage of the actuator with the valve casing in the relation shown, the bottom of the valve casing is preferably made as a separate piece 38 in the form of a cap which is screwed on the main part of the casing and in which the outlet opening 16 is formed. The slots 35 are formed with downward extensions through the bottom edge of the casing body, through which the arms may be passed. Cap 38, being then screwed in place, closes and obstructs such slot extensions.

All of the parts of this attachment, except the packing ring 30, cushion or buffer 34 and possibly the main valve element 18, are made of metal or any other suitably rigid and durable material.

A variation of means for securing the outlet valve to the faucet, which can be substituted for that above described, is shown in Figs. 5 and 6. Here a number of annular segments 39 of hard fiber or other suitable material are placed around the end of the faucet. They have a toric internal curvature shaped to fit more or less closely the circumference of the tube and the curve at the upper side of the bead 25. Collectively they substantially encircle the faucet terminal, as shown by Fig. 6. A rabbeted shoulder 40 is formed in the upper side of the segments to receive the flange 27 of the tube or sleeve 26. A compressible washer 41 is located between the opposed end surfaces of the faucet and valve casing 15. The shoulders 40 serve as abutments against which the sleeve reacts when forcing the valve casing against the faucet to compress the washer 41. The segments are applied to the faucet when the sleeve 26 is pushed back and are held in place by a spring ring 42 which is slipped into an encircling external groove of the segments. Or an elastic band can be placed in the groove instead of the spring ring shown. Such ring or band holds the segments in place until the coupling sleeve is passed over them and screwed on the valve casing. Thereafter the sleeve confines the segments and causes them to bind closely against the faucet bead.

Another variation of coupling means is shown in Fig. 7. Here the coupling sleeve 25 and washer 29 are substantially the same as those first de-

scribed. But instead of the packing ring 30, a ring 30a which does not extend under the end of the faucet is used. A rigid ring or washer 142 is placed on the valve casing underneath the packing ring, and the latter is compressed between the washers 29 and 142 when the coupling and valve casing are screwed together, and is thereby brought into binding engagement with the faucet and the coupling sleeve.

Still another means of attachment is shown in Fig. 8; this being designed for use with faucets which carry an external screw thread 43 at their extremity. Here the valve casing is made with a tubular extensin 15a internally threaded to fit the threads 43 of the faucet and with an internal shoulder 44 between which and the extremity of the faucet a compressible washer 45 is confined.

The principles of the invention can be embodied in other structural forms and combinations than that before described. One of such other embodiments is shown in Figs. 9-13. Here the main valve body 18a is a disk seated on the upper side of a base plate 46 and having a tubular stem 47 which fits rotatably in a central bearing passageway in the base plate 46 and projects beyond the under side of the base plate. A number of ports 48 in the disk and ports 49 in the tubular stem 47 are adapted to be placed in and out of registry with passages 50 in the base plate, by partial rotation of the valve body. The passages 50 open at one end in the surface on which the valve disk is seated, and at the other end in the sides of the passageway through the base plate and are suitably located for simultaneous registry with the ports 48 and 49.

The secondary valve 19a is the integral conical head of a stem 51, which extends and is slidable endwise through a guideway 52 in the center of the main valve; this guideway and the stem 51 being separated from the walls of the main valve stem 47 by an annular space wide enough to permit unimpeded flow of water when the ports 48 and 49 are placed in registry with the passages 50. Transverse passages 53 extend inward through the sides of the valve head 19a into intersection with a longitudinal passage 54 in valve stem 51, which extends from the point of intersection to the lower end of that stem. Valve 19a seats in a recess in valve 18a which is deep enough to close the outer ends of passages 53 when valve 19a is seated, preventing flow of water therethrough. But when the valve is lifted slightly, water can enter these passages and is caused to flow through the passage 54 with a whirling motion and emerge therefrom as a spray.

A ring 55 is secured, as by means of screw threads, to the end of the main valve stem 47 at a suitable distance from the under side of base plate 46. This ring supports three or more wedge members 56 on its upper side. A cup-like member 57 having numerous perforations in its bottom portion is secured tightly to stem 51 and is provided with side walls which embrace the ring 55 and lugs 58 extending from the upper edges of the side walls over the ring. Such lugs are equal in number, and are spaced equally, to the wedge members 56 and are so disposed that, when the cup 57 is rotated in one direction, they will ride up and pass over the wedge members, as shown by Figs. 11, 12 and 13. One of the lugs 58 has a downwardly extending tongue 59 projecting into a notch 60 in the ring 55. Preferably a housing 61 of rubber composition or other suitably yielding material is applied to the cup member

57 to surround the same. It is fashioned with a flange 63 to overlie the lugs 58, and is further fashioned into the form of a spout 62 below the perforated bottom of the cup 57 to confine outflowing water within desired limits. This cup is the means for operating the valve elements and will at times be designated the valve actuator.

The spacing of the ring 55 from the base plate, the height of the wedge members 56, and the thickness of the lugs 58 and overlying flange 63 of the housing 61, are established with such values that, when the cup member 57 is raised by the wedge members, flange 63 is brought against the base plate to form a water seal. Rise of these parts to the extent indicated also raises the secondary valve 19a enough to permit water to flow through the passageways therein.

Notch 60 is wide enough to permit rotation of the valve actuator to raise the secondary valve without turning the main valve, as is apparent from Figs. 11 and 12. Further movement in the direction of the arrows applied to Figs. 12 and 13 rotates the main valve and may be continued far enough to bring the ports 48 and 49 into registry with the passages 50. A stip pin 66 mounted on the base plate in a notch 67 of the valve disk 18a limits the rotation of this disk at points wherein the ports and passages are, respectively, in full registry and wholly occluded. The auxiliary valve can be opened also by upward movement of the actuator effected by pressure applied to the spout 62 or to any other part of the actuator.

This last described form of valve can be attached to a faucet by various means, for instance, any of the couplings previously described, and is here shown as attached by a duplicate of the coupling illustrated in Figs. 5 and 6. It is not essential that the part herein described as the base plate 46 be a substantially flat plate, for it could be variously formed provided only that it is capable of mounting the valve members in substantially the relationship here shown. That is, the base 46 or its like can be made with walls extending axially from its margin more or less like the side walls of the casing 15 shown in any of Figs. 2, 7 and 8 above the internal shoulder 17. In all of the forms precedently described, the casing 15 is essentially a base member having a passageway for water and a seating surface for a main valve.

I claim as my invention:

1. A compound outlet valve for faucets comprising a valve casing having a passage through it and a valve seat, and slots in its side wall intermediate the valve seat and the outlet of the casing, a main valve element arranged to bear on said seat and being separable therefrom in the direction away from the outlet, a secondary valve element cooperating with a passage through the main valve element and arranged to seat across the end of such passage which is more remote from the casing outlet, an actuator comprising a ring surrounding the casing and having arms extending through said slots with means for unseating the secondary valve element only when the actuator is displaced a limited distance in one direction and for unseating the main valve element also when displaced a further distance in the same direction.

2. A compound outlet valve for faucets comprising a valve casing having a passage through it and a valve seat, and a slot in its side wall intermediate the valve seat and the outlet of the casing, a main valve element arranged to bear on said seat and being separable therefrom in the direction away from the outlet, a secondary valve

element cooperating with a passage through the main valve element and arranged to seat across the end of such passage which is more remote from the casing outlet, an actuator comprising a ring surrounding the casing and having an arm extending through said slot with means for unseating the secondary valve element only when the actuator is displaced a limited distance in one direction and for unseating the main valve element also when displaced a further distance in the same direction, said slot being inclined so that reaction of a bounding wall thereof with said arm when the ring is rotated causes displacement of the actuator in the manner set forth.

3. A compound outlet valve for faucets comprising a casing having an inlet at one end, an outlet at the other end and a valve seat between the inlet and outlet, a main valve element cooperating with said seat for closing movement toward the outlet and opening movement away from the outlet, said valve element having a passage through it, a secondary valve arranged to seat across the end of said passage more remote from the outlet, said casing having slots in its sides inclined at an inclination to the direction in which the opening and closing movements of said valve elements take place, and a valve actuator comprising a hub portion within the valve casing near the main valve element, arms extending through said slots, and a tube projecting from said hub portion into the passage in the main valve toward the secondary valve, the terminal of said tube being nearer to the secondary valve element than the hub portion of the actuator is to the main valve element, whereby the actuator is enabled to unseat the secondary valve by a limited movement in one direction, without unseating the main valve, and to unseat the latter by further movement in the same direction.

4. A compound outlet valve having means for attachment to the delivery terminal of a faucet, comprising a base member having a passageway through it and an outlet which is downwardly directed when the valve is coupled to a faucet, a main valve element and a secondary valve element associated with the base member to be normally closed by pressure of fluid in the faucet, and an actuator movable linearly counter to the direction of flow of fluid from the faucet for opening the secondary valve element, and being rotatable about the axis of such linear motion for opening the main valve element, the base member having means limiting the first named movement of the actuator to a distance less than sufficient to unseat the main valve element.

5. A compound outlet valve having means for

attachment to the delivery terminal of a faucet, comprising a base structure having a delivery outlet and an encircling valve seat within such outlet, a main valve element arranged to close against such seat under pressure of water entering the base structure when in connection with a faucet, there being a passageway through the main valve, a secondary valve element arranged to seat across and close said passageway under pressure of entering water, a valve actuator associated with the base structure with provision for free movement linearly in the direction opposite to the direction of flow of water through said passageway, and also for rotation about the line of water flow, the base structure and actuator having cooperating cam and cam follower portions, of which the cam portion is inclined to the directions of opening and closing movements of the valve elements and is disposed to cause displacement of the actuator in the line of flow when rotated, and interacting means between the actuator and valve elements disposed to unseat the secondary valve element only when the actuator is displaced a limited distance linearly oppositely to the direction of flow, and to unseat the main valve element when the actuator is turned through a prescribed angle.

6. A compound outlet valve according to claim 5, in which the cam and cam follower portions, and the interacting means are relatively disposed and arranged to cause unseating of the secondary valve element, without unseating the main valve element, when the actuator is turned through a prescribed angle smaller than the angle through which it need be turned to cause unseating of the main valve element.
